DRILL TOOL

Walter Brauer, Corpus Christi, Tex.

Application September 30, 1948, Serial No. 51,929

7 Claims. (Cl. 255—23)

1

This invention relates to an earth boring apparatus, and more particularly but not by way of limitation, to a drilling head for drilling a bore around the outside of the drill pipe in an oil well bore.

With the present day shortage of steel casting and pipe, the removing of abandoned drill pipe and casing in already drilled oil, water and gas wells becomes very important. The present invention is generally concerned with a new type of well tool which may be utilized with any portable drilling rig for drilling around the outside of cemented drill casing whereby the casing may be removed. More particularly it utilizes a gear driven rotary mill encircling the casing to be salvaged in order to drill out a space around the cemented casing so that it may be removed from the well bore after it has been cut or blasted apart at any desired depth.

It is an important object of this invention to provide a drilling tool for drilling around the outside of drill casing normally left in a bore of an oil well whereby the cemented drill casing may be loosened so that it may be removed from the well bore.

Another object of this invention is to provide a drilling tool for drilling around cemented casing in a well bore thereby loosening the casing from the wall of the bore without the necessity of cutting the cement in the well bore, yet permitting removal of the casing so that the cement can be broken off after removal.

And still another object of this invention is to provide a well tool for drilling around a cemented casing in a well bore which is economical and efficient in operation, durable and thus providing for an inexpensive recovery of abandoned casing in oil, water, and gas wells.

And still another object is to provide a well drilling tool for drilling around abandoned casing in a well bore to permit removal thereof from the bore, wherein said tool may be utilized with any small size portable derrick capable of permitting a Kelly joint to be suspended between the rotary table and the drive stem of the outside drilling well tool.

And still another object of this invention is to provide a reamer type drilling head suspended in a well bore on a pair of parallel drive tubes wherein said reamer drills around cemented casing present in the bore in order to loosen the casing and permit removal thereof from the bore.

Other objects and advantages of the invention will be evident from the following detailed description, read in conjunction with the accom-

2

panying drawings, which illustrate my invention.

In the drawings:

Figure 1 is a vertical elevational view of the upper part of the drill head apparatus shown utilized with a fragmentary derrick.

Figure 2 is an extension of Fig. 1 showing the lower end of the drilling apparatus disposed in a well bore.

10 Figure 3 is a top view of the drilling mill head.

Figure 4 is a plan view of the rotary table and frame. Figure 5 is a sectional view taken on lines 5—5 of Fig. 1. Figure 6 is a sectional view taken on lines 6—6 of Fig. 3.

15 Referring to the drawings in detail, and particularly Figure 1, reference character 2 indicates any suitable type of derrick utilized with a portable rig unit (not shown) for the drilling of oil wells. The derrick is supported on the

20 derrick floor 4 in the usual manner, which in turn supports a table frame 6 having a rotary table 8 disposed therein. As clearly shown in Fig. 4, the rotary table 8 is secured to the upper side of a ring gear 8a which, in turn, is suitably

25 journaled (not shown) in the frame 6. The frame 6 is of box-like construction and is provided with an aperture 6a in the top thereof around the table 8 to permit free rotation of the table 8 upon rotation of the ring gear 8a as will be hereinafter set forth. The drill casing

30 10 to be salvaged (Fig. 1) is disposed in a well bore 12 of the oil, water or gas well and may extend down several hundred feet depending upon the amount of casing that was left abandoned in the well after the original drilling thereof. The frame 6 is anchored over the well bore 12 in

35 such a position that the rotary table 8 is in alignment with, although spaced from, the well casing 10 for purposes as will be hereinafter set forth.

40 The present drill head apparatus comprises a frame member 14 having a pivotable handle or bracket member 16 supported by a traveling block 18 suspended from the top of the derrick

45 2 in the usual manner. A pair of horizontally spaced swivel heads 20 and 22 are disposed adjacent the top of the frame member 14 and are provided with coupling members 23 and 24 interconnecting with a pair of spaced drive tubing

50 members 25 and 26. It will be apparent that the parallel tubing 25 and 26 are in alignment with the couplings 23 and 24 and extend upwardly through the frame 14 to be coupled with the swivel heads. A pair of thrust bearings 27

55 and 28 are disposed on the lower member 29 of

the frame 14 through which the tubing 25 and 26 extend. The outer periphery of the tubing 25 and 26 are provided with sprocket members 25b and 26b, respectively, as shown in Fig. 5. The sprockets 25b and 26b are connected with a sprocket chain 30 for a purpose that will be hereinafter set forth. A light weight Kelly member 31 Fig. 1 extends through the rotary table 8 upwardly into the frame member 14. The outer periphery of the Kelly member 31 is provided with a sprocket 31a, as shown in Fig. 5, connecting with the chain 30, and upon rotation of the Kelly member by the rotary table 8 as will be hereinafter set forth, the sprocket 31a drive will rotate the tubing members 25 and 26 simultaneously. It will be understood that the swivel heads 20 and 22 permit rotation of the tubings in the usual manner. It will also be understood that the tubings 25 and 26 and the Kelly 31 are each journaled in the lower member 29 of the table 14 to retain the tubings and Kelly in alignment during rotation thereof. The lower end of the Kelly 31 may extend freely into the upper end of the casing 10 as shown in Fig. 1 and as will be more fully hereinafter set forth.

The pair of drive tubes 25 and 26 extend downwardly from the swivel heads freely through tapered slip bowls 32 in the frame 6 and into the well bore 12. It will be apparent that the drive tubes may extend in the bore any length desired depending on the number of tube joints utilized. The tapered slip bowls 32 are formed in the usual manner with open upper and lower ends to permit free rotation of the tubings 25 and 26 therein, and are welded or otherwise suitably secured to the frame 6. It will be understood that the upper and lower portions of the frame 6 are cut away to receive the slip bowls 32. When it is desired to add extra joints to the tubings 25 and 26, slip members (not shown) are disposed in the slip bowls 32, so that the slips may support the lower joints of tubing 25a and 26a, during the uncoupling and coupling operation as is normal in drilling operations. The bottom end of each of the lower most tubing members 25a and 26a is connected with a drill head unit comprising a casting having a pair of diametrically opposed hollow cylindrical housing members 34 and 35 integral with a large ring or cylindrical housing 36 which encircles the drill casing 10. Hollow shafts 38 and 39 are threadedly secured by use of couplings 38a and 39a to the lower ends of the drive tubings 25a and 26a respectively, as shown in Fig. 6, and extend downwardly through the respective housings 34 and 35. An outwardly extending thrust ring 39b is formed on each of the hollow shafts 38 and 39 above the respective housings 34 and 35. A thrust bearing unit 39c is provided above and below each thrust ring 39b. Each pair of thrust bearings 39c are enclosed by a bearing housing 39d threadedly secured to the respective housing 34 or 35, and having a locking ring 39e in the upper end thereof loosely surrounding the respective hollow shaft 38 or 39 to retain the upper thrust bearing units 39c in assembly. It will therefore be apparent that the tubings 25a and 26a drive the hollow shafts 38 and 39 respectively. The housings 34 and 35, as well as the housing 36, are retained in a fixed longitudinal position on the hollow shafts 38 and 39 for simultaneous vertical movement with the shafts 38 and 39 and the drive tubings 25a and 26a. In addition, a suitable tubular shaped bearing material 39f is provided in each of the housings 34 and 35

around the respective shafts 38 and 39 to facilitate rotation of the shafts 38 and 39 in the housings 34 and 35. The shafts 38 and 39 extend below the housings 34 and 35 (Fig. 2) and are provided with bits 40 and 42 respectively secured to the lower end thereof. The lead or pilot bits are caused to rotate with the shafts and tubing simultaneously as will be hereinafter set forth.

The cylindrical housing 36 is provided with a cutaway portion or circular bore 44, as is most clearly shown in Fig. 6, in which is disposed the flange-like upper part 49 of the cylindrical mill member or reamer 46. The mill 46 is rotatable in the cylindrical housing 36 on a pair of rows of vertically spaced ball bearings 48. Complementary grooves 48a are provided in the outer periphery of the flange 49 and the side wall of the bore 44 to receive the ball bearings 48. A threaded transverse aperture 48b is provided in the flange 49 in communication with each of the grooves 48a to permit installation of the ball bearings 48. A suitable plug 48c is normally secured in each aperture 48b to prevent loss of the ball bearings 48. It will be apparent therefore that the ball bearings 48 operate as thrust members between the mill 46 and the housing 36 as well as facilitate rotation of the mill 46 in the housing 36. The outer periphery of the reamer 46 at a point near the lower end thereof is provided with a large gear member 50, while the lower end face of the reamer 46 is provided with a plurality of annular cutting teeth 52 as will be hereinafter set forth. The hollow shafts 38 and 39 are provided with small gears 56 and 58 at a point in alignment the large gear 50, and in meshing relationship therewith. The shafts 38 and 39 are provided with fluid ports 60 and 62 for lubrication of the cutting teeth 52, while the lower portion thereof (Fig. 2) are provided with ports 64 and 66 for lubrication of the lead bits which will be hereinafter set forth.

The rotary table 8 is rotated through a sprocket drive (chain 69) connecting with the sprocket 68, and any suitable source of motive power such as engine or the like. The sprocket 68 is secured to the outer end of a shaft 68a extending from a pinion gear 70 (Fig. 4). The shaft 68a is suitably journaled in the side of the rotary table housing 6. The pinion gear 70 meshes with the ring gear 6a to cause rotation of the rotary table 8 and Kelly 31 upon movement of the chain 69 as will be readily understood.

In operation the outside drilling apparatus is preferably utilized with any suitable portable rig unit wherein the Kelly joint 31 is rotated by the table 8 to cause a rotation of the tubing members 25 and 26 through the sprocket chain 30. The drill head housing 36 is disposed in the well bore and is supported by a plurality of joints of tubing 25 and 26 suspended in the bore. The depth of the drill head housing 36 in the bore is dependent upon the number of joints of tubing utilized. The lowermost joints 25a and 26a are simultaneously rotated with the upper joints 25 and 26, and are interconnected with the hollow shafts 38 and 39 in the cylindrical housings 34 and 35. The lower ends of the shafts carry the pilot bits 40 and 42. The reamer 46 is rotatably disposed in the drill head housing 36, and is adapted to be rotated by the shafts 38 and 39 through the medium of the gear connection 50, 56 and 58 to drive the cutting teeth 52. It will thus be apparent that as the traveling block 18 lowers the rotating tubing members

25 and 26 and kelly 31, the bits 40 and 42 are rotated in one direction (i. e. clockwise) for drilling bores at diametrically opposite points of the drill head 36, and thus prevent twisting or rotation of the drill head housings 34, 35 and 36. Simultaneously the reamer 46 is rotated in an opposite direction to that of the bits 40 and 42, counter-clockwise as shown, but not limited thereto, so that the teeth 52 will cut an annular bore around the outside of the cemented casing 10, and particularly at a point outside the cement on the casing. The kelly 31 moves downwardly into and rotates freely in the casing 10 during the drilling operation. It will be understood that the kelly 31 moves telescopically through the rotary table 8 during the drilling operation.

It will be apparent that as soon as a length of the tubing joints is drilled down, tubing slips may be disposed in the slip bowls 32, for supporting the tubing joints and drill head suspended in the bore. The tubings 25 and 26 are then disconnected from the swivel couplings 23 and 24 to permit raising of the frame 14 and kelly 31. Additional tubing joints are then connected with the tubings 25 and 26, and with the swivel couplings 23 and 24 in order to resume the drilling operation. Any desired length of abandoned drilling casing 10 may thus be loosened from the well bore. After a desired footage is thus loosened the drill casing may be cut off at the bottom, or blasted apart with an explosive, so that the casing may be removed from the well bore. Upon removal of the casing the cement is chipped off and removed in order to salvage the drill casing.

The cutting teeth 52 and the pilot bits 40 and 42 are provided with lubrication by mud and fluid circulation as is usual in drilling operations. Furthermore fluid circulation permits removal of the cuttings during the drilling operations. The circulation of the drilling fluid for the removal of the cuttings, is caused by the fluid entering the swivel circulating heads 20 and 22 from connecting hose members 70 and 72 connecting with any suitable source of supply and a mud pump (not shown). The fluid discharges from the swivel heads 20 and 22 through the tubings 25 and 26, hollow shafts 38 and 39 and out the ports 60, 62, 64, and 66, into contact with the mill teeth 52 and the pilot bits 40 and 42 respectively. From the teeth and bits, the cuttings are carried by the fluid up the well bore in the annular space drilled by the outside drilling head unit.

Changes may be made in the specification and drawings without departing from the spirit of the invention within the scope of the following claims as set forth.

I claim:

1. A tool for drilling an annulus around a casing disposed in a well bore and comprising a cylindrical housing surrounding the casing, means for supporting the housing in the bore, a freely rotatable reamer carried by the housing, said reamer having a cylindrical body having cutting teeth provided on the lower face thereof a pair of rotatable shafts carried by the housing and mounted at diametrically opposite sides of the reamer, gear connecting means between the shafts and the reamer, a rotary bit carried by each shaft below the reamer, rotating drive tubings suspended in the well bore and connecting with the shafts to cause rotation of the bits, said gear connecting means providing a

simultaneous rotation of the reamer, and means providing for rotation of the drive tubings.

2. A tool for drilling an annulus around a casing disposed in a well bore, and comprising a cylindrical housing, means for supporting the housing in the bore, a freely rotatable reamer carried by the housing and surrounding the casing, said reamer having a cylindrical body provided with cutting teeth on the lower end thereof, a pair of rotatable shafts disposed in the housing and mounted at diametrically opposite sides of the reamer, gear connecting means between the shafts and the reamer, a bit carried by each shaft below the reamer, rotating drive tubings suspended in the well bore and connecting with the shafts to cause rotation of the bits, said gear connecting means providing a simultaneous rotation of the reamer, and fluid circulating means for the reamer and the bits, and means providing for rotation of the drive tubings.

3. A drilling tool for use with a derrick in drilling around a casing disposed in a well bore, comprising a pair of drive tubings suspended from the derrick and extending into the well bore, said tubings disposed adjacent the outer periphery of the casing, a housing connecting with the tubing and surrounding the casing, said housing having an annular body portion and a pair of diametrically opposed cylindrical portions, a shaft carried in each of the cylindrical portions and connecting with the tubings, an annular reamer rotatably mounted on the body portion of the housing around the casing, a gear carried by the reamer, a gear carried by each of the shafts and cooperating with the reamer gear, a plurality of circumferential teeth on the reamer, a rotary bit carried by each of the shafts below the reamer, and means for rotating the drive tubings and shafts, said gears providing a simultaneous rotation of the bits and the reamer.

4. The combination of a well drilling apparatus and a drilling tool comprising a derrick, a rotary table, means for supporting the table, a rotating kelly extending upwardly from the table, a pair of drive tubings suspended from the derrick and extending into the well bore, a housing surrounding the casing, a reamer rotatably mounted on the housing for drilling an annulus around the casing, a pair of rotatable shafts disposed in the housing adjacent the reamer and connecting with the drive tubings, gear connecting means between the shafts and the reamer, drive connecting means between the kelly and the tubings to cause simultaneous rotation of the drive tubings with the kelly, said gear connecting means providing a simultaneous rotation of the reamer with the drive tubings, and rotating bits carried by the shafts below the reamer to assist the reamer in drilling the annulus around the casing.

5. The combination of a well drilling apparatus and a drilling tool comprising a derrick, a rotary table, means for supporting the table a rotating kelly extending upwardly from the table, a pair of drive tubings suspended from the derrick and extending into the well bore, a housing surrounding the casing, a reamer rotatably mounted on the housing for drilling an annulus around the casing, a pair of rotatable shafts disposed in the housing adjacent the reamer and connecting with the drive tubings, gear connecting means between the shafts and the reamer, means connecting between the kelly and the tubings to cause simultaneous rotation of the drive tubings

with the kelly, said gear connecting means providing a simultaneous rotation of the reamer with the drive tubings, and rotating bits carried by the shafts and disposed below the reamer to assist the reamer in drilling the annulus around the casing, and means providing fluid circulation through the tubings to the reamer and the bits.

6. A tool for drilling an annulus around a casing disposed in a well bore, comprising an annular housing of a size to pass over the casing, means for supporting the housing in the bore an annular reamer rotatably carried by the housing, said reamer being of a size to pass over the casing, diametrically opposed housings formed on the first mentioned housing, shafts rotatably mounted in each of the second mentioned housings, means for rotating said shafts, intermeshing gears on the shafts and the reamer, a pilot bit on one end of each of the shafts, and fluid discharge ports in said shafts adjacent said gears and said pilot bits.

7. A tool for drilling an annulus around a casing disposed in a well bore, comprising an annular housing of a size to pass over the casing,

means for supporting the housing in the bore an annular reamer rotatably carried by the housing, said reamer being of a size to pass over the casing, diametrically opposed housings formed on the first mentioned housing, shafts rotatably mounted in each of the second mentioned housings, means for rotating said shafts, intermeshing gears on the shafts and the reamer, a pilot bit on one end of each of the shafts, and fluid discharge ports in said shafts adjacent said gears and said pilot bits.
